UNITED STATES PATENT OFFICE

118,293

DESIGN FOR A LIGHT PROJECTOR

Otto E. Trautmann, Irondequoit, N. Y., assignor
to Bausch & Lomb Optical Company, Roch-
ester, N. Y., a corporation of New York

Application September 30, 1939, Serial No. 87,442

Term of patent 7 years

To all whom it may concern:

Be it known that I, Otto E. Trautmann, a citizen of the United States and a resident of the town of Irondequoit, county of Monroe and State of New York, have invented a new, original, and ornamental Design for Light Projector, of which the following is a specification, reference being had to the accompanying drawing, forming a part thereof,

Fig. 1 is a side elevation of a light projector embodying my new design.

Fig. 2 is a top plan view thereof.

Fig. 3 is a rear elevation thereof.

I claim:

The ornamental design for a light projector, substantially as shown.

OTTO E. TRAUTMANN.
